C. WINKLER

MANTLE OF MOLDS FOR CASTING STEREO TYPE PLATES

Filed Feb. 5, 1927

INVENTOR
CARL WINKLER

BY *Dunwoody*
ATTORNEY

UNITED STATES PATENT OFFICE.

CARL WINKLER, OF BERN, SWITZERLAND.

MANTLE OF MOLDS FOR CASTING STEREO TYPE PLATES.

Application filed February 5, 1927. Serial No. 166,228.

In casting stereotype plates the mantle of the mold very frequently gapes somewhat under the influence of the heat of the molten metal flowing into the mold. This distortion cannot be properly prevented by simply cooling the mantle by water passing through a hollow chamber behind the wall on which the matrix lies, because the mantle must have a certain temperature, in order to obtain good plates. It has been suggested to provide an insulating air chamber between said wall and the water mantle, and, by so doing, better results are obtained, although the quantity of water required is excessive. By the present invention this idea is further developed by making the mantle with a chamber behind said wall so deep that it occupies the greater part of the inside of the mantle, and by providing the back of the mantle with a relatively thin water chamber.

By thus cooling the back of the mantle, instead of the wall carrying the matrix, the back offers a greater resistance to the gaping of the mold, and better plates are obtained, which is of particular importance when the plates are used for printing without being first bored. Further, the thin water mantle enables cold water to be rushed through without requiring an excessive quantity.

In the drawing illustrating my invention by way of example.

Fig. 1 shows a cross section of such a mold mantle, and Fig. 2 a longitudinal section of same on A—B in Fig. 1.

The wall *a* of this mantle carries the

matrix in the usual way. Behind this wall *a* is provided the deep hollow chamber *b*, which contains air, or any insulating substance and is provided with openings *b'* for the circulation of air or other substance therethrough, and the back *c* of the mantle is provided with a water chamber *d*. Water enters this chamber at one point, for example, at *e*, and leaves at another point, such as *f*.

The connecting rods for moving the mantle are attached to projecting lugs *g*, *h*. What I claim and desire to secure by Letters Patent of the United States is:

1. A mantle for a mold for casting stereotype plates, having an air chamber occupying the greater part of the inside of the mantle behind the wall carrying the matrix, with a water cooling chamber for the back wall, substantially as, and for the purpose, set forth.

2. A mantle for a mold for cooling stereotype plates, having an air chamber occupying the greater part of the inside of the mantle behind the wall carrying the matrix, with a water cooling chamber for the back wall, and lugs for attaching the operating gear, substantially as set forth.

3. In a mold for casting stereotype plates, a mantle having a comparatively large air chamber in rear of the wall carrying the matrix and a comparatively shallow water chamber between the air chamber and back wall of the mantle.

In testimony whereof I have signed my name to this specification.

CARL WINKLER.
